(57) **CLAIM**

The ornamental design for a water gun, as shown and described.

DESCRIPTION

FIG. 1 is a front, right, and top perspective view of a water gun, showing my new design;

FIG. 2 is a rear, left, and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of the encircled portion labeled “9” in FIG. 1; and,

FIG. 10 is a perspective view of the water gun, shown in an alternative configuration.

The dot-dash broken lines in FIGS. 1 and 9 denote the boundaries of the enlarged areas and form no part of the claimed design. The evenly spaced broken lines in the drawings depict portions of the water gun that form no part of the claimed design.
